United States Patent Office

Des. 178,600
Patented Aug. 28, 1956

178,600

SIGN DISPLAY BOARD

Malcolm H. Gibson, Coolidge, Ariz.

Application January 27, 1956, Serial No. 39,950

Term of patent 14 years

(Cl. D1—12)

FIG. 1

FIG. 2

FIG. 3

FIG. 4

Figure 1 is a front elevational view of a sign display board showing my new design;

Figure 2 is a top view thereof;

Figure 3 is a back elevational view thereof; and

Figure 4 is an end elevational view thereof.

I claim:

The ornamental design for a sign display board, as shown.
